UNITED STATES PATENT OFFICE.

WILLIS H. COLBY, OF DETROIT, MICHIGAN.

BLACKING STAND.

1,411,607.

Specification of Letters Patent. Patented Apr. 4, 1922.

Application filed August 21, 1919. Serial No. 318,928.

To all whom it may concern:

Be it known that I, WILLIS H. COLBY, a citizen of the United States, residing at Detroit, in the county of Wayne and State of Michigan, have invented a new and useful Blacking Stand, of which the following is a specification.

The device forming the subject matter of this application is a blacking stand, and the 10 object of the invention is to provide novel means for mounting the foot rest and for holding the flexible polishing strip in operative relation to the foot rest.

In the accompanying drawings:—

15 Figure 1 is a top plan wherein the lid has been swung backwardly to an open position; Figure 2 is a section on the line 2—2 of Figure 1; and Figure 3 is a fragmental section taken on the line 3—3 of Figure 1.

20 The cabinet comprises side walls 5. The back of the cabinet is denoted by the numeral 11. A platform 16 is provided, the side edges of which carry depending cleats 19 united by securing elements 20 to the

25 sides 5. Strips 27 are secured to the side walls 5, above the platform 16. There are notches or seats 28 in the upper edges of the strips 27. A front piece 29 fits between the sides 5 and is located above the platform 16, 30 the front piece abutting against the forward ends of the strips 27 as shown in Figure 1.

A back piece 30 fits between the sides 5 and is located above the platform 16, the back piece abutting against the rear ends of the strips 27. The front piece 29 and the back piece 30 are secured to the strips 27 by hinges 31. The parts of the hinges have no relative movement, the hinges having the function of angle brackets or connections, uniting the 40 parts 29 and 30 with the members 27.

The ends of guide bars 32 are mounted in the notches 28 of the strips 27 and are held in place by securing elements 33, passing inwardly through the upper portions of the 45 sides 5 and engaging the ends of the guide bars. The numeral 34 denotes a foot rest supported on the guide bars 32 and provided with a rib 35 received slidably between the guide bars. The foot rest 34 is supplied with 50 a heel recess 36 and with a heel stop 37.

Bearings 38 are mounted on the platform 16 on opposite sides of the guide bars 32 and carry rollers 39. A flexible polishing strip 40 is looped about the rollers 39 and extends above the guide bars 32 and the foot rest 34. 55

The top of the cabinet is closed by a vertically swinging lid 46 connected to the back piece 30 by hinges 47.

When it is desired to use the cabinet for blacking purposes, the lid 46 is swung backwardly into open position. The foot rest 34, when not in use, may be supported on the platform 16, to the end that the lid 46 may be closed. When it is desired to use the foot rest, the rib 35 on the foot rest is mounted 60 between the guide bars 32. The foot rest 34 may be adjusted longitudinally of the guide bars 32 as occasion may demand, so that when the flexible polishing strip 40 is reciprocated on the rollers 39, the strip will 65 70 coact with the desired part of the shoe.

Having thus described the invention, what is claimed is:—

1. A blacking device including a cabinet; guides extended across the cabinet; a foot rest supported on the guides and comprising a rib received between the guides, the foot rest being movable longitudinally of the guides; and directing elements for a flexible member, located on opposite sides of the 80 guides.

2. A blacking device comprising a cabinet including side walls; strips mounted on the side walls and having notches; a guide received in the notches; a foot rest carried by 85 the guide; front and rear members located between the side walls and abutting against the strips; means for securing said members to the strips; a platform supporting said members; and guiding means for a flexible element, carried by the platform and located on opposite sides of the guide.

In testimony that I claim the foregoing as my own, I have hereto affixed my signature in the presence of two witnesses.

WILLIS H. COLBY.
